UNITED STATES PATENT OFFICE.

LEWIS LARSEN, OF MENOMINEE, MICHIGAN, ASSIGNOR TO HEYWOOD-WAKEFIELD COMPANY, OF BOSTON, MASSACHUSETTS, A CORPORATION OF MASSACHUSETTS.

METHOD OF PRODUCING A SIMULATED STAKE AND STRAND FABRIC ARTICLE.

Application filed June 1, 1926. Serial No. 113,041.

This invention relates to an improved method of producing a simulated stake and strand fabric article and it consists in the matters hereinafter described and more particularly pointed out in the appended claims.

The main object of the present invention is to provide a novel method of producing articles of furniture, vehicle bodies and the like which include a substantially tubular or endless body covering, which simulates in appearance a covering made of a stake and strand fabric of reed or reed fibre, and by which method, the articles of furniture, vehicle bodies and the like may be made at a greatly reduced cost and at an increase in the speed of production.

A further object of the invention is to provide a method of the kind described wherein a blank of sheet material such as a good quality of paper is cut to a predetermined pattern or outline and is simultaneously slit to form connected strand portions and through the slits of which stakes are inserted over and under desired strand portions after which the ends of the blank are attached together to form a substantially tubular covering, thereafter attached as an entirety to the article frame to produce the finished article.

My invention consists generally in the manner, steps, acts and sequence thereof, whereby the above mentioned objects together with others which will hereinafter appear, are attainable and my invention will be more readily understood by reference to the accompanying drawings illustrative thereof and wherein:

Fig. 1 is a view in plan elevation of a blank cut from a piece of suitable sheet material and simultaneously slit in the proper manner and ready for the lacing or inserting of associated stakes.

Fig. 2 is a view similar to Fig. 1 showing the blank as it appears after the insertion of the stakes.

Fig. 3 is a perspective view on an enlarged scale of a fragment of the slitted blank after insertion of the stakes therein.

Fig. 4 is a detail sectional view on an enlarged scale through the staked blank or after insertion of the stakes, the plane of the

section being indicated by the line 4—4 of Fig. 2.

Fig. 5 is a detail sectional view on an enlarged scale as taken through one end margin of the staked blank, the plane of the section being indicated by the line 5—5 of Fig. 2.

Fig. 6 is a perspective view of an article frame adapted to receive and to have secured to it, the staked blank shown in Fig. 2.

Fig. 7 is a perspective view of a vehicle body formed by attaching a staked blank shown in Fig. 2 to the article frame shown in Fig. 6.

Fig. 8 is a detail vertical section through one side of the vehicle body shown in Fig. 7 as taken on the line 8—8 thereof.

Fig. 9 is a detail horizontal sectional view as taken on the line 9—9 of Fig. 8.

Fig. 10 is a fragmentary view in elevation of the overlapping ends of the covering before application to a vehicle body frame, illustrating one manner in which said overlapping ends may be attached together.

Fig. 11 is a vertical sectional view through the same as taken on the line 11—11 of Fig. 10.

Fig. 12 is a horizontal detail sectional view as taken on the line 12—12 of Fig. 10.

The drawings illustrate the several steps of my improved method as employed in the production of a vehicle body such as a baby carriage body of the closed end or "gondola" type and I will describe the method in accordance therewith but it is to be understood that the same is intended as by way of illustration and description only and not by way of limitation because my improved method may also be employed or followed out in the production of other articles where its peculiar characteristics makes it of advantage to do so.

The vehicle body illustrated in Fig. 7 of the drawings includes a body frame which comprises a rectangular elongated flat base 1, a horizontally disposed substantially rectangular shaped top frame member 2 and upright U shaped side frame member 3—3, which frame members are made of suitable dowel stock bent to form as best shown in Fig. 6. Each side frame member 3 includes upright end members 3^a—3^a and a connecting horizontal bottom member 3^b, which is disposed

in a plane below that of the base, said base having recesses 1^a in its corners in which portions of the upright members 3^a—3^a are secured in any suitable manner. The rectangular top frame member, includes side rails or parts 2^a—2^a and front and rear end members 2^b—2^b, the side rails resting upon and being fixed to the top ends of the upright members 3^a—3^a of each side frame member.

10 The sides and ends of the frame just described are adapted to be covered by a body fabric or covering of a stake and strand fabric simulating material, which at the time of application to the frame is tubular or of endless form, Fig. 2 showing the fabric or covering before the ends thereof have been connected together to provide such tubular or endless form. Said fabric is preferably made of a fibrous material such as a good 20 quality of paper of the desired thickness and is cut from a sheet to provide the blank 5 best shown in Fig. 1. Said blank is of an irregular strip form and includes a mid or body portion 6 with a side portion 7 at each 25 end thereof which side portions each terminate in an extension part 8 of a length, somewhat greater than one half the length of said body portion. In the finished fabric, the portion 6 forms one end of the tubular covering 30 to be attached to the vehicle body frame, the portions 7—7 form the sides thereof and the extensions 8 are attached together to form the other end of the covering.

35 The portions 7 which will be hereinafter referred to as the "side portions" are disposed in oppositely and downwardly curved planes and at rather shallow angles to the plane of the mid portion 6 and each extension 8 is disposed in the same manner with respect to said 40 portions 7, as said portions bear with respect to said mid portion 6, the end edges of said extensions 8 being preferably arranged at a right angle to the top and bottom edges of said extensions.

45 In the body, side and end extension portions of the blank are provided, longitudinally extending rows of spaced slits 9, each row being suitably spaced from the adjacent rows to provide rows of strand simulating portions 10 50 extending transversely across the blank and in planes at substantially right angles to the edges of the blank through which said planes extend, the rows of strand portions being arranged alternately with respect to intermediate strand connecting or bond portions 11. The top and bottom rows of slits 9 are spaced inwardly from the top and bottom edges of the blank (which is shown in an endwise position in Figs. 1 and 2 for sake of convenience) 55 thus leaving top and bottom selvage margins 12 and 13 there-along, while all the rows of slits terminate at their ends short of the edges of the extensions 8 thus forming selvage margins 14—14 on said extensions. Furthermore, as shown herein but not necessarily so,

the second slit in each row of slits, counting from each end of the blank is omitted to form a transverse band or unslit portion 15. Thus each end row of strand portions is isolated or in other words is separated from the next adjacent row of strand portions by the transverse band 15 as indicated at 10^a in Figs. 1 and 10. From the foregoing it is apparent that there is an unslit selvage or margin bounding the slit blank. Should it be desired to incorporate certain designs, or configurations in the portions 6 and 7 of the finished fabric, to enhance the appearance thereof, this may be easily done by omitting certain slits in predetermined rows of slits thus leaving portions in the blank wherein some of the strand portions 10 are of a greater area as for instance as shown at 10^b in Figs. 1 and 2.

The blank thus slit is now ready to receive the stakes, one for each row of strand simulating portions 10. The stakes 16 employed are preferably those used in the reed weaving industry and may be either of natural reed or reed fibre the latter usually including a steel wire core which gives it strength but permits it to be flexed as required. Each stake which may or may not be cut to proper length before use, is inserted through the slits defining one row of strand simulating portions 10 and in simulating regular "over and under" stake and strand fabric, the stakes are so inserted that alternate strand portions engage on one side of the stakes and the intermediate strand simulating portions are engaged on the other side of said stakes. In inserting the stakes through the strand simulating portion of the adjacent rows, the corresponding strand simulating portions are disposed upon opposite sides of the stake in alternation to those just described, so that if a horizontal row of strand simulating portions is considered, alternate portions are disposed on one side of all of said stakes and the intermediate portions are disposed on the opposite side of all of the stakes, the ends of said stakes always being disposed on the same side of the blank as best shown in Figs. 3 and 4 which is the "inside" after the fabric has been attached to an article frame. In inserting the stakes into the slit-blank, no stakes are inserted into the end-most rows of strand portions 10^a—10^a between the selvage margin 14 and unslit band portion 15, the same being left in this condition for a purpose to appear later.

It is to be noticed that the bond portions 11 which extend transversely or from top to bottom of the blank are in no manner severed or slit so far as the top and bottom selvage margins 12 and 13 are concerned and that they therefore act to connect said margins together and impart a stability or stiffness to the blank when considered transversely and thus assist the stakes in this action. Again the bonding portions perform another func-

tion in that they cause the strand simulating portions to be flexed or placed under a slight tension after insertion of the stakes whereby the stakes are not only tightly gripped but are prevented from shifting laterally and are thus maintained in their proper and intended position so that the regularity of appearance of the finished article in which the fabric is embodied is in no manner marred or caused to appear uneven. A construction as just described has great strength in a plane parallel with the stakes but is so flexible in a lengthwise direction as to easily conform to the desired shape.

15 As is apparent the rows of slits may be continuous in length, or in other words the slits may be so formed as to make the strand portions in the form of ribbons, or bands extending the length of the slits. However under 20 such a construction, there would be nothing to maintain the stakes against lateral shifting as is apparent and even the strands might become displaced so that such a construction would not be so practical as the one wherein 25 the slits in each row are spaced apart providing the strand portions above described.

After the blank has been "staked" as described, the end portions are brought together in overlapping relation so that the isolated strand portions 10^a on one end register with the like bond portions at the other end thus bringing the selvage margin 14 on one end to overlap the band portion 15 on the other end and the selvage margin on the second mentioned end to underlap the band 15 on the first mentioned end. Thereafter the registering strand portions 10^a are offset to one side or the other of the plane of the fabric and a stake member 16^a is inserted through the slits, over and under the strand portions thus securing the ends of the blank together so that the same is now a fabric of tubular form. Should it be desired, the stake 16^a may be dispensed with and the ends of the blank brought into overlapping relation and cemented together but such a connection is not so strong as that first described which is also advantageous as it adds to the symmetrical appearance of the associated end of the finished article as best shown in Fig. 10, with a band and a selvage margin disposed upon opposite sides of the plane of the registering strand portions.

In applying such a slit and staked and now tubular fabric or frame covering member above described, upon a vehicle body frame as shown in Fig. 6 I place the top portion of the fabric over the bottom end of the frame and work the fabric until its top selvage may be engaged partways around the parts 2^a—2^b of the top members 2 of the frame, the overlapping ends of the fabric being positioned at one end of the frame, with the stake 16^a in the median plane of the frame. The fabric may be worked or pulled to make it conform

with the frame and its bottom selvage margin 13 is brought to coincide with the bottom frame parts, the selvage margins being secured to the associated frame parts by tacks or brads 17. In affixing the selvage margins to said frame parts I find it preferable to drive the tacks or brads through the selvage margins in the planes of the bond portions 11 as best shown in Fig. 9 so that said stakes are not only secured against endwise withdrawal but the heads of the tacks or brads do not so project as to be objectionable in any manner.

It will be noticed from Fig. 8 that a slight curvature may be provided in the sides of 80 the carriage body and this curvature will be more or less at different portions of the body so that the covering will easily conform to the shape of the frame to which it is applied. With the fabric on the frame as before mentioned, there will be a design on each side and on one end of the body so that the whole will be of symmetrical appearance. It is also preferable that the finish for the body such as the desired coats of paints or enamels be 85 applied after the covering or fabric is on the frame because the possibilities of soiling the same is thus greatly reduced. My improved method although described in connection with the production of a baby carriage body, may 90 also be employed in the production of other articles where its peculiar characteristics makes it advantageous to do so.

95 Inasmuch as this disclosure will readily suggest to others skilled in the art to which this method appertains, various methods whereby the substantial objects of my invention can be attained, I do not wish to be limited to the specific stated manner of procedure nor to the precise steps, acts or stated sequence 100 thereof, except as may be found necessary by the limitations in the appended claims.

I claim as my invention:—

1. The method of producing an article having a frame and a simulated stake and strand fabric covering which consists in providing a covering member of sheet material having rows of slits therein terminating short of the edges of the sheet to form selvage margins, bringing the ends of the covering member together in overlapping relations with some of the strands in one end in register with those in the other end, inserting a stake through the registering strands to secure the ends of the covering member together so that said covering member is of tubular form and attaching said covering member to the frame.

110 2. The method of producing an article having a frame and a covering simulating a stake and strand fabric, which consists in providing a sheet of material of a length approximating the circumference of the frame and having rows of longitudinally extending spaced slits therein terminating short of the 115 ends of the sheet to provide strand portions 120

in the body of the sheet with an unslitted top and bottom selvage margin, inserting stakes under and over desired strands, bringing the ends of the sheet into overlapping relation 5 with the endmost strands in registration, inserting a stake through said registering strands to secure said ends together and to

make the sheet tubular in form and applying the tubular fabric, thus produced, to the frame with the selvage margins in engagement with 10 and secured to portions of said frame.

In testimony whereof, I have hereunto set my hand, this 24th day of May, 1926.

LEWIS LARSEN
